(57) **CLAIM**

The ornamental design for a vehicle attachable land leveling device, as shown and described.

DESCRIPTION

FIG. 1 is a top isometric view of the vehicle attachable land leveling device showing our new design;
FIG. 2 is a bottom isometric view thereof;
FIG. 3 is front view of FIG. 1;
FIG. 4 is a right side view of FIG. 1;
FIG. 5 is a rear view of FIG. 1;
FIG. 6 is a left side view of FIG. 1;
FIG. 7 is a top view of FIG. 1;
FIG. 8 is a bottom view of FIG. 1; and,
FIG. 9 is a cross-sectional view taken from line 9-9 in FIG. 7.
